(57) **CLAIM**

The ornamental design for siding panel having grooved ends, as shown and described.

DESCRIPTION

FIG. 1 is a left front perspective view of a siding panel having grooved ends showing our new design, the wavy lines in the center of all the figures represents indeterminate length, the broken line showing of an extra siding panel having grooved ends, fasteners and an installation clip are for environmental purposes only and form no part of the claimed design; FIG. 2 is an enlarged right rear perspective view thereof; and, FIG. 3 is a right rear perspective view of an alternate embodiment of a siding panel having grooved ends showing our new design, the front view being the same as FIG. 1.
